COMBINED EARRING CLASP AND ORNAMENT ATTACHMENT DEVICE

Selig M. Danzig, New York, and Gerald Skolnik,
Brooklyn, N. Y.

Application January 19, 1949, Serial No. 332

Term of patent 7 years

(Cl. D45—9)

To all whom it may concern:

Be it known that Selig M. Danzig and Gerald Skolnik, citizens of the United States of America, and residents of Bronx, N. Y., and Brooklyn, N. Y., respectively, have invented a new, original, and ornamental Design for Combined Earring Clasp and Ornament Attachment Device, of which the following is a specification, reference being had to the accompanying drawing forming part thereof, in which:

Fig. 1 is a front elevational view of a combined earring clasp and ornament attachment device embodying our new design;

Fig. 2 is a side elevational view thereof; and
Fig. 3 is a top plan view thereof.

We claim:

The design for a combined earring clasp and ornament attachment device, substantially as shown.

SELIG M. DANZIG.
GERALD SKOLNIK.
